BY John M. Cole

ATTORNEY

UNITED STATES PATENT OFFICE.

EMORY S. LEWIS, OF NEW YORK, N. Y.

DESIGN FOR A LIGHTING-FIXTURE COVER.

Application filed July 28, 1924. Serial No. 10,274. Term of patent 7 years.

To all whom it may concern:

Be it known that I, EMORY S. LEWIS, a citizen of the United States, and a resident of the city of New York, county of Kings, and State of New York, have invented a new, original, and ornamental Design for Lighting-Fixture Covers, of which the following is a specification, reference being had to the accompanying drawing, forming a part hereof.

In these drawings:

Fig. 1 is a front view of the lighting fixture cover, and

Fig. 2 is a side elevation of the lighting fixture cover.

I claim:

The ornamental design for a lighting fixture cover substantially as shown.

EMORY S. LEWIS.
